UNITED STATES PATENT OFFICE.

FRANK E. TONIUTTI, OF FOREST PARK, ILLINOIS.

LEGGING.

Application filed August 10, 1922. Serial No. 580,873.

To all whom it may concern:

Be it known that I, FRANK E. TONIUTTI, a citizen of the United States, and a resident of Forest Park, Cook County, and State of Illinois, have invented certain new and useful Improvements in Leggings, of which the following is declared to be a full and clear and exact description.

This invention relates to leggings, and its 10 principal object is to provide a legging of neat and attractive appearance and one which will lie flat when not in use. Another object is to provide a legging, having creases, or sharply defined edges at the front and 15 back with means for securing the leggings upon a leg of the wearer without destroying the creases. Another object is to provide a legging which will reach above the knee, and having means for securing the legging upon 20 a leg of the wearer without destroying the creases. With these and other objects and advantages in view, this invention consists in the several novel features hereinafter fully set forth and claimed.

25 The invention is clearly illustrated in the drawing accompanying this specification, in which:

Fig. 1 is a side elevation of a legging embodying a simple form of the present invention; Fig. 2 is a side elevation showing certain flaps or side members of the legging unfolded; Fig. 3 is a horizontal section taken on the line 3—3 of Fig. 1 showing the side members of the leggings slightly spread 35 apart to more clearly illustrate the parts that secure the legging on the leg; and Fig. 4 is a detail horizontal section taken on the line 4—4 of Fig. 1.

Referring to said drawing, the reference 40 character 5 designates one side member of the legging, 6 the front side member, and 7 the rear side member, which form the other side of the legging, and 8 designates a strap which is stitched to the side member 5 and is 45 detachably secured to the front side member 6 by the ordinary snap fasteners 9. The side members are stitched together along their front and rear edges, as shown at 10, 11, and preferably, said side edges and the 50 top and bottom of said side members are bound with tape 12. The side members are shaped as shown in the drawings to give the desired shape to the legging when in use, and its forward portion is extended upward, as 55 shown, to reach above the knee of the wearer. The side members 6, 7, overlap and are de-

tachably secured together with the ordinary snap fasteners 13, arranged along their overlapping edge portions, and said edge portions are preferably faced with strips of 60 facing material 14, 15.

To hold the legging on the leg of the wearer without distorting or disarranging its creases, an elastic strip 16 is employed, adjacent the upper portions of the legging, 65 which strip is fastened to the edge portions of the side members 6, 7, at 17, 18, by stitches or otherwise, and a loop 19 is secured upon the side member 5 through which the elastic strip 16 extends. As a preference, the 70 elastic strip may be contained in a casing 20 of light weight material.

The legging is preferably, although not necessarily so, constructed of rain proof or water proof material or any material which 75 is made water proof by suitable means, as is well understood by those skilled in the art to which this invention pertains, and to prevent rain from entering between the overlapping edge portion of the side members 80 6, 7, the member 7 is formed with a trough-like edge portion 21 which intercepts the rain. This trough-like edge portion is formed by folding the edge of the material upon itself, as seen in Fig. 4 and stitching 85 the same together by stitches 22 leaving the free edge 23 projecting from the remainder of the goods. The cloth being water proof any water entering between the flaps 6, 7, 90 will be caught by the projecting edge portion or rib 23, and will be conveyed downward instead of passing between the flaps, and inconveniencing the wearer.

While leggings constructed in accordance with the above description may be worn 95 with any other garments, they have been designed for use in connection with a rain and storm proof coat upon which I have filed an application on even date herewith under the Serial No. 580,877. For this purpose, the leggings are provided with snap fastener members 24, adjacent their upper edges, which may be snapped upon coacting snap fastening members that are secured upon the rain and storm proof coat, as is 100 more fully set forth in my above mentioned co-pending application.

When in use with the side members 6, 7, fastened together, the elastic strip 16 grips the leg of the wearer and supports the 110 legging thereon without distorting the shape of the legging. It is to be understood

that the elastic strip 16 is of less length than the circumference of the legging at the place where the strip is attached, so that it, and not the legging grips the leg. 5 By reason of this arrangement, the creases of the legging are not disturbed but are maintained in the legging while being worn.

More or less variation of the exact details of construction is possible without departing from the spirit of this invention; I desire, therefore, not to limit myself to the exact form of the construction shown and described, but intend, in the following claims, to point out all of the invention disclosed herein.

I claim as new, and desire to secure by Letters Patent:

1. A legging having front and back creased edges, and comprising a side legging member, front and back side legging members secured to the other side member at the front and rear edge portions thereof, fastening members for securing said front and back side members together and an elastic strip secured to the free edge portions of said front and back members, adjacent their upper ends, said elastic strip being free from the creases at the front and back, whereby the upper end of the legging may 20 be secured on the leg of a user without disturbing the creases.

2. A legging having front and back

creased edges, and comprising a side legging member, front and back side legging members secured to said first mentioned side 35 legging member at the front and rear edges thereof, an elastic strip secured to the free edge portions of said front and back side members, adjacent their upper ends, and a loop on the first mentioned side member 40 through which said elastic strip extends, said elastic strip being free from the creases at the front and back, whereby the upper end of the legging may be secured on the leg of a user without disturbing the creases. 45

3. A legging having overlapping front and back side legging members, snap fasteners for securing said members together, the upright edge portion of one of said legging members being formed with a trough-like water shedding portion along its edge, and the other legging member being arranged to lap over said trough like water shedding portion. 50

4. A legging comprising overlapping front and back side legging members, snap fasteners for securing together the overlapping portions thereof, the free edge portion of the inner side member being doubled upon itself and stitched to the outer face 60 of the legging member, to leave a projecting rib forming with said face a trough for shedding water. 65

FRANK E. TONIUTTI.
